Primary Examiner — Darlington Ly*Assistant Examiner* — D. Ryan Tisdale(57) **CLAIM**

The ornamental design for a car mat, as shown and described.

DESCRIPTION

FIG. 1 is a front, right and bottom perspective view of a car mat showing my new design;

FIG. 2 is a rear, left and top perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is perspective view shown in an environment of use; and,

FIG. 10 is an enlarged partial view of FIG. 1.

The broken lines illustrating a part of the car in FIG. 9 are for the purpose of illustrating environmental subject matter that forms no part of the claimed design. The remaining broken lines in the drawings are for the purpose of illustrating portions of the car mat that form no part of the claimed design.

1 Claim, 10 Drawing Sheets(56)
